To all whom it may concern:

Be it known that we, Lester A. Demkier and Kenneth O. Hostetter, citizens of the United States, residing at Dubuque, in the county of Dubuque and State of Iowa, have invented a new, original, and ornamental Design for a Molding Machine or the like, of which the following is a specification, reference being had to the accompanying drawing, forming part thereof.

In the drawing:

Figure 1 is a front elevational view of a mold-
ing machine embodying our new design;

Fig. 2 is a side elevational view thereof, and
Fig. 3 is a rear perspective view thereof.

We claim:

The ornamental design for a molding machine
or the like, substantially as shown.
